[57] **CLAIM**

The ornamental design for an electrosurgical instrument, as shown and described.

DESCRIPTION

FIG. 1 is a perspective view of an electrosurgical instrument as seen from the rear top and left side;

FIG. 2 is an enlarged perspective view of the distal end of an electrosurgical instrument;

FIG. 3 is a top plan view thereof;

FIG. 4 is a side elevational view thereof, the opposite side elevational view being a mirror image thereto;

FIG. 5 is a bottom plan view thereof;

FIG. 6 is a front elevation view thereof; and,

FIG. 7 is a rear elevational view thereof.
